UNITED STATES PATENT OFFICE.

ADDO M. ROBERTS AND EDWIN G. WILLIAMSON, OF GREENVILLE, PENNSYLVANIA.

PNEUMATIC TOOL.

1,267,698.

Specification of Letters Patent. Patented May 28, 1918.

Application filed September 7, 1917. Serial No. 180,234.

To all whom it may concern:

Be it known that we, ADDO M. ROBERTS and EDWIN G. WILLIAMSON, both citizens of the United States, and both residing at Greenville, in the county of Mercer and State of Pennsylvania, have invented certain new and useful Improvements in Pneumatic Tools, of which the following is a specification.

10 This invention relates to improvements in pneumatic tools, and is especially adaptable for tools for cutting rivet heads and in other operations requiring the use of the cold chisel. Our invention has for its object to

15 provide a safe and convenient tool for this purpose and in particular an improved valve for devices of this kind.

The invention comprises a cylinder provided at one end with a tool of the kind desired and having a reciprocating air valve at the opposite end connected with a suitable source of compressed air. A hammer in the form of a piston is slidable in the cylinder to impart blows to the tool. 20 Passages are provided for admitting air from the source of supply to either end of the cylinder by the reciprocation of the valve, which is operated by means of a lever and connecting link secured to the valve end 25 of the cylinder, the valve having passages cut therein for establishing proper communication between the source of air supply and the cylinder. By rocking the lever the valve may be moved to effect the reciprocation of the piston in the cylinder.

Referring to the accompanying drawings, Fig. 1 is an elevation of our tool showing certain parts broken away to show the air passages.

40 Fig. 2 is a section on line 2—2 of Fig. 1, showing the piston in position to deliver a blow, and the valve in position to admit air to the lower end of the cylinder.

Fig. 3 is a section similar to Fig. 2, showing the piston in striking position and the valve in position to admit air to the opposite end of the cylinder.

Fig. 4 is a cross section of the valve.

In the drawings, 1 is a cylinder having a bushing 2 threaded to one end, the bushing being provided with a threaded portion 3, to which is screwed a sleeve 4 formed with a chamber 4' therein. Slidable within the cylinder 1 is a piston or hammer 5. The shank 6 of a tool 7 slidably mounted in the bushing 2 and the sleeve 4 normally pro-

jects into the cylinder 1, as shown in Fig. 2. That portion of the shank of the tool within the chamber 4' is provided with a flange 8 forming a stop which limits movement of the tool relatively to the cylinder. This stop prevents the tool from being ejected should the piston be driven against its shank when it is not being firmly held against the work during the cutting operation. We also provide the chamber 4' with a compressible buffering device 9 preferably of a non-metallic substance, as rubber hose, adapted to be engaged by the flange 8 when the tool is being driven forward. Other means can be used for this purpose, such as a spring, but we find that a non-metallic substance offers little resistance to the tool and reduces vibration and noise and gives a more desirous buffering action. After the tool has been driven forward by the impact of the piston it is returned to normal position by the pressure of the tool against the work.

Air under pressure is admitted alternately to opposite ends of the cylinder 1, to drive the piston back and forth in the cylinder to deliver a series of successive blows to the tool. We accomplish this by providing the end of the cylinder opposite the tool with a head in the form of a casing 10 having a valve chamber 11 therein, and having oppositely disposed inlet and outlet pipes 12 and 13, respectively, which serve also as handles for the device. To permit the inlet of air from the inlet pipe to the valve chamber 11 there is provided a passage 14 and a port 15. Communication is established between the valve chamber and one end of the cylinder 1 through passage 16, while it is established between the valve chamber and the opposite end of the cylinder by means of port 17 (see Fig. 1) connecting with pipe 18 leading to the other end of the cylinder at 19. Exhaust port 20 permits air to escape from the valve chamber 11 to exhaust pipe 13. An opening 21 near the tool end of the cylinder permits air to escape therefrom.

Passage of air through the various ports is controlled by means of a slide valve or plug 22 in valve chamber 11 having a passage 23 extending diametrically therethrough near one end of the plug, such passage communicating with a passage 24 at right angles to passage 23 (see Fig. 4). Passage 23 is adapted to register with inlet port 15 and with exhaust port 20 during different stages of operation, while passage

24 registers with the cylinder communicating port 16. To permit the passage of air from inlet port 15 to port 17, we provide a groove 25 on the circumference of the 5 valve, the groove having a right angular continuation 26 which is adapted to register with port 17.

The end of the valve chamber 11 is provided with a bushing 27 through which 10 passes a rod 28 secured to valve plug 22 and to the projecting end of which is pivoted a lever 29 fulcrumed to a link 30 connected to support 31 secured to the casing 10. By 15 rocking lever 29 the valve plug 22 may be reciprocated in the valve chamber.

Assuming the valve to be in the position shown in Fig. 2, air passes from inlet pipe 12 along passage 14, through port 15 into groove 25 on valve plug 22, around the 20 groove to port 17 and then through pipe 18 and port 19 where it enters the cylinder to effect the return of the piston to position ready for a working blow. With the piston in this position air within the cylinder will 25 hold the piston in the position shown, while excess air escapes through port 21. When it is desired to deliver a blow to the tool, the operator throws the lever 29 forward, moving valve plug 22 to the position shown in 30 Fig. 3, when the air will pass down passage 23 and along passage 24 into the port 16 and thence into the cylinder, driving the piston to the end of the cylinder as shown in Fig. 3. The operator may then return the piston 35 to the valve end of the cylinder by rocking lever 29 backward to the position shown in Fig. 2, when air will again pass along the pipe 18 into the cylinder at 19. By the escape of part of the air through port 21 the 40 piston is prevented from being returned forcibly to the valve end of the cylinder. Port 21 also serves to prevent compression in the lower end of the cylinder when the piston is moving forward to strike a blow.

Compression in the valve end of the cylinder when the piston is returning is prevented by escape of air from the cylinder through port 16 in casing 10 into passage 24 in valve plug 22 and out passage 23 into exhaust port 20 and thence to exhaust pipe 18.

The valve is normally automatically held in inoperative position, as shown in Fig. 2, by reason of the fact that should it accidentally be moved to operative position as shown in Fig. 3, back pressure in the cylinder would speedily return it. The operator, by practice, may readily regulate the force of the blow by regulating the movement of the lever 29.

We claim as our invention:

1. A pneumatic tool comprising a cylinder provided at one end with a tool, a hammer for impacting with said tool slidable in said cylinder, a reciprocable valve connected with a source of air supply at the opposite end of said cylinder, a lever pivoted to said cylinder and connected with said valve to effect its reciprocation, and passages in said cylinder and valve adapted to normally hold the valve in a position where air pressure is admitted to said cylinder to hold said hammer out of engagement with said tool.

2. A pneumatic tool comprising a cylinder provided at one end with a tool, a hammer for impacting with said tool slidable in said cylinder, a reciprocable valve connected with a source of air supply at the opposite end of said cylinder, a lever pivoted to said cylinder and connected with said valve to effect its reciprocation, passages controlled by said valve for operating said hammer, and means controlled by the air pressure from said source of supply for normally holding the valve in inoperative position.

In testimony whereof, we have hereunto subscribed our names.

ADDO M. ROBERTS.

EDWIN G. WILLIAMSON.
